UNITED STATES PATENT OFFICE

2,569,410

VACUUM APPARATUS FOR FILLING CAPSULE-LIKE RECEPTACLES WITH FLUID

Edmond P. De Craene, Westchester, Ill., assignor to Crane Co., Chicago, Ill., a corporation of Illinois

Application September 25, 1948, Serial No. 51,213

1 Claim. (Cl. 226—116)

1

This invention relates to a novel vacuum apparatus for filling capsule-like receptacles with a liquid.

In order to obtain an appreciation of the background of this invention, it should be understood that in the manufacture of temperature responsive units that are to be filled with a liquid, it is essential that they be filled completely and therefore that all air spaces within the unit are eliminated, realizing that the presence of air will cause erratic functioning of the unit. Likewise, any air or gas otherwise absorbed in the liquid during the course of filling the capsule will be conducive to inconsistent results and errors.

Therefore, it is one of the more important objects of this invention to provide the apparatus and method of filling temperature responsive units such as the capsules, for example, described in patent application Serial Number 212 filed January 2, 1948, now abandoned. In devices of the type referred to it is, of course, important that these thermal units operate with considerable accuracy and, at the same time, permit their manufacture and assembly with a minimum of expense and freedom from trouble.

It is another important object to provide an apparatus and method which positively eliminates air content simultaneously from the two sources above referred to and yet, at the same time, to permit a larger number of units to be filled than heretofore. Thus, the process lends itself readily to quantity production.

It should be further understood that the thermal units above referred to contain an actuating stem axially movable in response to internal fluid pressures behind a snugly fitted diaphragm therewithin and are useful in the same manner as described in the device per se shown in patent application Serial Number 790,638 filed December 9, 1947, now Patent No. 2,548,516, to actuate a switch, shaft or other mechanism by such axial movement of the actuating stem. The diaphragm as illustrated is preferably provided with a socket within which the stem 13 is snugly received.

As will hereinafter become apparent, it is desirable from a production standpoint to eliminate unnecessary adjustments previously caused by the air content normally accumulating within the thermal unit and also to have the actuating stem protrude from the unit uniformly or at a constant dimension on all units. It should be understood that unless this is controlled during the filling of the units, such stem projection may vary considerably.

2

It is, therefore, a further object of this invention to provide an apparatus in which the thermal units are held in a fixture which controls the over all-stem dimension before placing the devices in the vacuum chamber as hereinafter described in greater detail.

Other objects and advantages will become more readily apparent upon proceeding with the specification read in light of the accompanying drawings, in which

Fig. 1 is a sectional assembly view of a general assembly of the novel apparatus.

Fig. 2 is a plan sectional view of the device on the line 2—2 of Fig. 1.

15 Similar reference numerals refer to similar parts throughout the several views.

Referring now to Fig. 1, a vacuum vessel generally referred to as 1, preferably consisting of upper and lower halves 2 and 3 respectively, bolted together by means of the bolts 4 or held together to form a pressure-tight joint by any other suitable means, provides the chamber 5 in which a jig for holding receptacles to be filled, generally referred to as 6, is positioned resting upon the base 7 of the lower half portion 3. The depth of the fluid in which the filling jig is placed is represented by the dotted lines 8. The particular fluid used may be a silicone polymer fluid, the latter being odorless, inert and not injurious to rubber or the like, and having a known and constant rate of expansion over a wide temperature range, and a low vapor pressure.

30 The complete assembly, in addition to the filling jig, consists of the outlet piping 9 for attachment to a vacuum pump (not shown) and provided with a vacuum gage as indicated, the piping 9 being preferably held in sealed relation to the container 2 by means of the packing 11.

35 The thermal units or receptacles are placed in the filling jig generally designated 6, the thermal units being separately mounted upon the apertured supporting portion 12 with the projecting stems 13 abutting against the base frame 14. Each of the thermal units 15 is open as at 16 to allow for the liquid in which they are placed to be received. The lower supporting base frame or plate 14 and the upper supporting member 17 are maintained in assembled relation by means of the bolts 18 and the nuts 19. As indicated, the stove-bolt 20 retains the apertured member 12 in fixed relation to the plate 6.

40 45 50 55 While the members 14 and 17 are shown in substantially circular form, it should, of course, be apparent that they may be of any suitable shape to conveniently and economically receive

the thermal units or other vessels to be filled. A detailed construction of the thermal units or receptacles has been omitted. It is deemed unnecessary because it is more clearly described in detail in the pending patent application referred to.

In considering the operation of this device by means of the vacuum pump, as air is evacuated from the jar 1, it is also evacuated from the thermal units thereby permitting the liquid to flow into the said units 15. It will also be apparent that at the same time any entrapped air or gas in the liquid will be liberated. When the thermal units 15 are filled, the cover 2 of the vacuum jar is removed and the sealing screws and gaskets (not shown) but described in connection with patent application, Serial Number 212 will be positioned in fluid sealing relation in the openings of the units before they are removed from the fluid in the jar. Thus it will be clear that the thermal units 15 are filled with a predetermined measured amount of silicone polymer fluid or the like, and further than the specific construction of the jig or holding fixture base plate 6 cooperates with the specific construction of the thermal unit being filled to provide for such measured vacuum fill as hereinabove described.

The foregoing operation will assure filling the units completely with the liquid free from any air or gas.

It should, of course, be understood that the specific embodiment of the apparatus may be changed considerably from that shown and described and it is the desire therefore to be limited only by the scope of the appended claim.

I claim:

In an apparatus for filling with liquids free of air or gases such receptacles as thermal elements

or the like having an axially movable projecting stem, the apparatus including a vacuum jar with upper and lower portions in sealed relation, upper and lower plates within the vacuum jar for supporting the receptacles to be filled, a vacuum pump line connected with an upper portion of the said jar whereby as air is evacuated from the interior of the said jar it is also evacuated from the receptacles to permit the filling liquid to flow into an upper portion of the said receptacles and concurrently liberate any entrapped air or gas therewithin, the said plates being held together to clamp a plurality of receptacles therebetween, the lower plate supporting the axially movable projecting stem of the receptacle to be filled, apertured means provided on said lower plate to at least partially receive a lower neck portion of the said receptacle, the receptacle projecting stem extending within said apertured means beyond the lowermost neck portion of the said receptacle to bear against said lower plate.

EDMOND P. DE CRAENE.
